J. D. MORGAN,
METAL PUNCHING MACHINE,
APPLICATION FILED MAY 26, 1919.

1,349,975.

Patented Aug. 17, 1920.

John D. Morgan
INVENTOR

UNITED STATES PATENT OFFICE.

JOHN D. MORGAN, OF SUMMIT, NEW JERSEY, ASSIGNOR TO STEEL UTILITIES, A CORPORATION OF NEW YORK.

METAL-PUNCHING MACHINE.

1,349,975.

Specification of Letters Patent. Patented Aug. 17, 1920.

Application filed May 26, 1919. Serial No. 300,008.

To all whom it may concern:

Be it known that I, JOHN D. MORGAN, a citizen of the United States, residing at Summit, in the county of Union and State of New Jersey, have invented certain new and useful Improvements in Metal-Punching Machines, of which the following is a specification.

My invention relates to machines for punching metal sheets, plates, beams and the like, wherein the work is successively progressed, stopped and positioned relatively to punching mechanism, or other tool-equipped means to be punched or operated upon thereby at predetermined positions or locations.

One object of the present invention is to keep the plate, sheet, beam, or like work in exact position with relation to a part traveling in definite relation with, and under the control of, a distance determining or regulating device, and more especially to provide mechanism of the kind indicated which co-operates with an automatically operating, distance determining or regulating device. Other objects and advantages of the invention will be set forth hereinafter, or will be obvious herefrom, or may be learned from practice with the invention, the same being realized or secured through the means, instrumentalities and combinations pointed out in the appended claims.

The invention consists in the novel parts, constructions, arrangements, combinations and improvements herein shown and described.

The accompanying drawings herein referred to and constituting a part hereof, illustrate one embodiment of the invention, and together with the description serve to explain the principles thereof.

Of the drawings:

Figure 1 is a fragmentary top plan of a mechanism constructed in accordance with the principles of the invention, showing the magnetic head in section;

Fig. 2 is a fragmentary side elevation, looking at Fig. 1 from the lower side thereof;

Fig. 3 is a fragmentary elevation, looking at Fig. 1 from the right; and

Fig. 4 is a fragmentary section of a somewhat different form of the head.

In the illustrated embodiment of the drawings the present invention is shown by way of example as applied to a metal punching machine substantially the same as that shown in U. S. Patent No. 1,241,258 of L. A. Hawthorne, dated Sept. 25, 1917, although it will be understood that the invention is applicable to other kinds of metal punching and like machines.

In the exemplified embodiment of the present drawings, certain parts of the machine illustrated and described in said U. S. Patent No. 1,241,258 are shown, to explain the application of the present invention to the machine of said patent. Such parts of the patented machine are indicated by the same reference numerals as in said Patent No. 1,241,258, for the sake of convenience in description.

The work *x* is supported and progressed by rollers 1, journaled in a suitable supporting frame or frames, and which may be driven in the manner shown and described in said prior patent. The co-operating devices which arrest the traveling work relatively to the punches or other tool equipped means at the proper predetermined points, to locate the operations at the desired places on the work, comprise a screw shaft 40 and the co-operating mechanisms which are shown in said prior Patent No. 1,241,258, and which need not be described in detail herein. It will be understood, however, that such mechanism may be operated under the control of a distance record sheet, as explained in said prior patent.

In co-operation with the screw shaft 40 is a carriage or head 25 traveling along guides 15, which guides extend along the path of the work, the travel of the carriage being controlled by the distance determining means as explained in the patent. The engaging member or latch 45 is carried by the head or carriage 25, and is timed to engage with the screw shaft 40 by the distance determining mechanism, the shaft then rotating under the control of the distance determining mechanism, while the latch is engaged with the shaft to complete the distance reading, as fully explained in the patent.

The reference numerals thus far employed correspond to those applied to the same or

corresponding parts in said Patent No. 1,241,258, to avoid prolixity in the present description.

The head 25 with which the work engages 5 has a portion 50 which extends out transversely from the main portion of the head into the path of the work α as it travels along the rolls 1. In accordance with the present invention, the work engaging portion 10 of the head is an electro-magnet, the work being held thereto by magnetic attraction. In such embodied form, the head comprises a contact bar 51 which is in exact position with respect to the distance determining device. The contact bar 51 is supported by a plurality of rods 52 which serve as cores for the windings 53 of the electro-magnets. Rods 52 are accurately fitted into a laterally extending plate, being 15 preferably fitted thereinto by a beveled fit and held in place by nuts 54 screw-threaded on to the rods. The windings 53 are supported on the rods 52 as already described.

Suitable means are provided for supplying 20 current to the windings as the head 25 travels along the guideways 15. For this purpose, as embodied, two trolley wires 55 and 56 are strung along the path of travel of the carriage, and two trolleys 57 and 58 25 are mounted upon the head or carriage 25 by insulated mountings 60 and 61, respectively, and slide along the wires 55 and 56, respectively. The trolleys have wires extending therefrom, respectively, which are 30 carried by a cable 62 to the magnet windings 53.

In Fig. 4 an embodiment of a special 35 form of head or contact bar is shown, which is adapted for use with sheets and plates of metal. On the face of the contact bar 51 are provided supports, such as apertured lugs 65, in which apertures are slidably carried rods 66 attached to a plate 67 extending along the face of the contact bar 51 and 40 adapted to lie on the upper face of a sheet or plate α of metal supported and progressed upon the rolls 1. In Fig. 4 the outer or front edge of the plate 67 is upwardly curved to permit a fed-in plate α to 45 slide thereunder and the supporting rods 66 may have heads 68 to limit the downward movement of plate 67.

Means are provided for cutting off the 50 electric current from the magnets whereby the work may be more readily separated therefrom at the completion of the punchings or other operations upon the work. As embodied, a switch 69 is shown in the trolley circuits for this purpose.

By the present invention, the work is 55 kept securely to position against the head, which is especially desirable with relatively light work such as many kinds of sheets or plates. It is also especially useful where 60 the work may be drawn longitudinally or

transversely by the head to position it relatively to the punches or other tool equipped means. Other advantages and adaptations will be obvious herefrom or may be learned by practice with the invention.

It will be understood that changes may be made in the particular mechanism shown and described, without departing from the principles of the invention, and without sacrificing its chief objects and advantages.

What I claim is:—

1. In a machine for operating upon metal plates or beams, a carriage traveling under control of a distance determining device, a head fixed to said carriage and in engagement with the work, means impelling the work against said head and means for magnetizing said head to prevent rebound or displacement of the work relatively to the head.

2. In a machine for operating upon metal plates or beams, a carriage traveling under control of a distance determining device, a magnetic head fixed to said carriage and in engagement with the work, and means impelling the work against said head.

3. In a machine for operating upon metal plates or beams, a carriage traveling under control of a distance determining device, a head fixed to said carriage and in engagement with the work, magnet windings on said head, trolleys on said carriage, and trolley wires therefor extending along the path of travel of the carriage, and means impelling the work against said head.

4. In a machine for operating upon metal plates or beams, a carriage traveling under control of a distance determining device, a magnetic head fixed to said carriage and in engagement with the work and means for demagnetizing said head, and means impelling the work against said head.

5. In a machine for operating upon metal plates or beams, a carriage traveling under control of a distance determining device, a head fixed to said carriage and in engagement with the work, and means for magnetizing and demagnetizing said head, and means impelling the work against said head.

6. In a machine for operating upon metal plates or beams, a carriage traveling under control of a distance determining device, a magnetic head fixed to said carriage and in engagement with the work, said head having means for engaging a plurality of surfaces of the work, and means impelling the work against said head.

7. In a machine for operating upon metal plates or beams, a carriage traveling under control of a distance determining device, a magnetic head fixed to said carriage and in engagement with the work, said head having means for engaging the front end and the adjacent side of a plate to be operated upon by the machine.

8. In a machine for operating upon metal plates or beams, a carriage traveling under control of a distance determining device, a head fixed to said carriage and in engagement with the work, means for impelling the work against said head, magnet windings on said head, trolleys on said carriage, and trolley wires therefor extending along the path of travel of the carriage, and means for cutting off the current from the trolley wires to demagnetize the head.

9. In a machine for operating upon metal plates or beams, a carriage traveling under the control of a distance determining device, a magnetic head fixed to said carriage and shaped to abut on the front end and also on the adjacent horizontally disposed side of a beam or plate.

10. In a machine for operating upon metal plates or beams, a carriage traveling under the control of a distance determining device, a magnetic head fixed to said carriage and shaped to abut on the front end and also on the adjacent horizontally disposed side of a beam or plate, and means impelling the work against the head to engage at its end and side with the head.

11. In a machine for operating upon metal plates or beams, a carriage traveling under the control of a distance determining device, a magnetic head fixed to said carriage and shaped to abut on the front end and also on the adjacent horizontally disposed side of a beam or plate, and means impelling the work against the head to engage at its end and side with the head, and spring means for holding the work in contact with the head.

12. In a machine for operating upon metal plates or beams, a carriage traveling under the control of a distance determining device, a magnetic head fixed to said carriage and shaped to abut on the front end and also on the adjacent horizontally disposed side of a beam or plate, and means impelling the work against the head to engage at its end and side with the head, and spring means for automatically receiving the work and for holding the work in contact with the head.

In testimony whereof I have signed my name to the specification.

JOHN D. MORGAN.
